UNITED STATES PATENT OFFICE

GORDON E. ROEDDING, OF GRAND RAPIDS, MICHIGAN, ASSIGNOR TO GRAND RAPIDS
BRASS COMPANY, OF GRAND RAPIDS, MICHIGAN

LATCH

Application filed December 13, 1929. Serial No. 413,732.

The main object of this invention is to provide a reversible latch readily adjusted for either a right or left hand latch and having a long throw in either adjustment.

5 A further object is to provide a reversible latch having these advantages in which the parts are few, economical to produce and easily assembled.

10 Objects pertaining to details and economies of my invention will definitely appear from the description to follow. The invention is defined in the claims.

15 A structure embodying the features of my invention is clearly illustrated in the accompanying drawing, in which:

Fig. 1 is a fragmentary view of a door and its casing with one of my improved latches mounted thereon, the latch casing being shown in section on line 1—1 of Fig. 2.

20 Fig. 2 is a fragmentary view with the latch in section on a line corresponding to line 2—2 of Fig. 3, the spring supporting link being adjusted to a central position relative to the bolt for convenience in illustration. The latch is inoperative when in this position.

25 Fig. 3 is an inverted fragmentary view of the latch proper with the parts in position shown in Fig. 2.

30 Fig. 4 is a fragmentary rear or inverted view with the bolt shown in actuated position by full lines and in retracted position by dotted lines.

Fig. 5 is a rear perspective view of the back 35 plate of the latch.

In the accompanying drawing 1 represents a door casing and 2 the door. The body 3 of the latch is preferably a stamping. This latch body is provided with a back plate 4 having special features which will be referred to as the description proceeds.

The rear wall 5 of the housing has an opening therein to receive the bolt 6. The front wall 7 has an opening through which the bolt 45 projects. In forming the rear opening a por-

tion 8 is struck inwardly as shown in Fig. 2, this inturned portion having a pivot 9 formed thereon engaging a pivot opening in the top of the bolt.

The bolt is chambered and has a longitudinal slot 10 in its top wall through which the arm 12 on the spring supporting link 13 projects. This arm has a lug 14 on its upper end overlapping the top of the bolt so that a sliding connection is provided for the link to the bolt. 50

At its opposite end the link is provided with a pivot 15 which is selectively engageable with pivot seats 16 designated also by the letters "L" and "R" on Figs. 3 and 5, indicating right and left. These pivot seats are 55 disposed on opposite sides of and uniformly spaced from the bolt pivot 9.

A bridge piece 17 is struck up from the rear portion of the back plate overlapping the pivoted end of the link, thereby retaining 60 its pivot in engagement with the pivot seats. This bridge piece also has an upwardly projecting lug 18 disposed in alignment with the pivot and constituting a pivot member for the bolt, the lug engaging within the chamber 65 of the bolt.

A coiled spring 19 is engaged with a spherically curved seat 20 provided therefor on the arm 12, its other end being supported by a lug 21 struck inwardly from one of the side walls 70 of the bolt, see Fig. 2. With the parts thus arranged the spring acts to urge the bolt to latching position, the spring being placed under additional stress as the bolt is swung from this latching position or retracted. 75

To hold the bolt in retracted position against the tension of the spring, the bolt is provided with downwardly projecting detents 22 which are adapted to engage with the slot-like keepers 23 disposed at each side of the central position of the bolt. The thrust of the spring tends to swing the bolt rearwardly so that it is automatically engaged with these keepers when swung to retracted 80 85 90

position or to position bringing the detents 22 in alignment with the openings 23.

With this arrangement of parts the latch has a long stroke or throw, that is, the bolt is 5 free to swing a considerable distance beyond the center of the latch, so that it is very effective in sealing doors such as for refrigerators, or in taking up or compensating for wear and compression on the gaskets of refrigerator doors and the like.

10 In most latches of this type the normal or stop position of the bolt under the action of its spring is a central position, thereby limiting the effective compressing action to the latch center position, whereas in the latch of this application this throw and consequent take-up are very substantially increased, and this without increasing the size of the latch.

15 Stops 24 are struck inwardly from the front wall of the housing in position to be engaged by the lug 14 on the arm of the spring supporting link. Only one of these stops is in operative position at one time as the lug clears the other. These stops can be positioned 20 without increasing the size of the latch to permit a greater throw than is possible with the latch illustrated. The advantage of this is, as stated, much greater than that of the ordinary reversible latch.

25 The keeper 25 is provided with a tappet 26 adapted to disengage the bolt detent from its keeper when the door is swung to closed position with the latch retracted, thereby allowing the spring to act to engage the latch.

30 I have illustrated and described my improvements in an embodiment especially designed for refrigerator doors or other relatively heavy doors. I have not attempted to describe other embodiments or adaptations as it is believed that this disclosure will enable 35 those skilled in the art to embody or adapt the same as may be desired.

Having thus described my invention what I claim as new and desire to secure by Letters Patent is:

40 1. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed 45 on opposite sides of the plane of the pivot to coact with said detent, a spring supporting link having a pivot selectively engageable with said seats in said back plate, the swinging end of said link having an upwardly projecting arm at its front end disposed through 50 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link, and spaced stops on said casing coacting with 55 said lug on said link.

55 2. In a latch, the combination with a housing provided with a back plate, a chambered bolt pivotally mounted in said housing and having a slot in its top wall and a rearwardly projecting detent, said housing back plate having pivot seats disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 60 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

65 2. In a latch, the combination with a housing provided with a back plate, a chambered bolt pivotally mounted in said housing and having a slot in its top wall and a rearwardly projecting detent, said housing back plate having pivot seats disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 70 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

75 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 80 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

85 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 90 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

95 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 95 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

100 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 105 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

110 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 115 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

120 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 125 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

130 3. In a latch, the combination with a housing provided with a back plate, a chambered bolt pivotally mounted in said housing and having a slot in its top wall and a rearwardly projecting detent, said housing back plate having notch-like pivot seats on its rear edge disposed on opposite sides of the bolt pivot and also having keeper openings disposed on opposite sides of the plane of the pivot to coact with said detent, a spring supporting link having a pivot selectively engageable with said seats in said back plate, the swinging end of said link having an upwardly projecting arm at its front end disposed through 135 said slot in said bolt and having a lug overlapping the top of the bolt, said bolt having a spring supporting lug in spaced relation to said arm, a coiled spring arranged in said bolt in supporting engagement with its said spring supporting lug and said arm on said spring supporting link.

posed through said slot in said bolt and having a lug overlapping the top of the bolt, said arm having a spherically curved spring seat thereon, said bolt having a spring supporting lug in spaced relation to said arm, and a coiled spring arranged in said bolt in supporting engagement with its said spring supporting lug and said arm on said spring supporting link.

5. In a latch, the combination with a housing provided with a back plate, a chambered bolt pivotally mounted in said housing and having a slot in its top wall, said housing back plate having pivot seats disposed on opposite sides of the bolt pivot, a spring supporting link having a pivot selectively engageable with said seats in said back plate, the swinging end of said link having an upwardly projecting arm at its front end disposed through said slot in said bolt and having a lug overlapping the top of the bolt, said arm having a spherically curved spring seat thereon, said bolt having a spring supporting lug in spaced relation to said arm, a coiled spring arranged in said bolt in supporting engagement with its said spring supporting lug and said arm on said spring supporting link, and spaced stops on said casing coacting with said lug on said link.

6. In a latch, the combination with a housing provided with a back plate, a chambered bolt pivotally mounted in said housing and having a slot in its top wall, said housing back plate having pivot seats disposed on opposite sides of the bolt pivot, a spring supporting link having a pivot selectively engageable with said seats in said back plate, the swinging end of said link having an upwardly projecting arm at its front end disposed through said slot in said bolt and having a lug overlapping the top of the bolt, said arm having a spherically curved spring seat thereon, said bolt having a spring supporting lug in spaced relation to said arm, and a coiled spring arranged in said bolt in supporting engagement with its said spring supporting lug and said arm on said spring supporting link.

7. In a latch, the combination with a housing provided with a back plate, a bolt pivotally mounted in said housing, said housing back plate having notch-like pivot seats on its rear edge disposed on opposite sides of the bolt pivot, a spring supporting link having a pivot selectively engageable with said seats in said back plate, the swinging end of said link being slidably associated with said bolt, a spring mounted on said bolt in supporting engagement with said link, said back plate also having a bridge piece struck up at the rear edge thereof overhanging the rear end of said spring supporting link and provided with an upwardly projecting bolt engaging lugs alined with the bolt pivot.

8. In a latch, the combination with a hous-

ing provided with a back plate, a bolt pivotally mounted in said housing, said housing back plate having notch-like pivot seats on its rear edge disposed on opposite sides of the bolt pivot, a spring supporting link having a pivot selectively engageable with said seats in said back plate, the swinging end of said link being slidably associated with said bolt, and a spring mounted on said bolt in supporting engagement with said link, said back plate also having a bridge piece struck up at the rear edge thereof overhanging the rear end of said spring supporting link.

9. In a latch, the combination with a housing provided with a back plate, a bolt pivotally mounted in said housing, said housing back plate having notch-like pivot seats on its rear edge disposed on opposite sides of the bolt pivot, a spring supporting link having a pivot selectively engageable with said seats in said back plate, the swinging end of said link being slidably associated with said bolt, and a spring mounted on said bolt in supporting engagement with said link.

10. In a latch, the combination with a housing, a chambered bolt pivotally mounted within said housing and having a slot in its top wall, a spring supporting link having an upwardly projecting arm on its swinging end disposed through said slot in said bolt and having a lug overlapping the top of the bolt, said housing being provided with link supporting means disposed at opposite sides of the bolt pivot and with which the link may be selectively engaged, a spring mounted within said bolt to engage said arm on said link, and spaced stops in said casing limiting the swing of said bolt in latch engaging direction, said casing and bolt being provided with coacting detents and keepers whereby the bolt is retained in retracted position.

11. In a latch, the combination with a housing, a chambered bolt pivotally mounted within said housing and having a slot in its top wall, a spring supporting link having an upwardly projecting arm on its swinging end disposed through said slot in said bolt and having a lug overlapping the top of the bolt, said housing being provided with link supporting means disposed at opposite sides of the bolt pivot and with which the link may be selectively engaged, and a spring mounted within said bolt to engage said arm on said link.

12. In a latch, the combination with a housing, of a chambered bolt pivotally mounted in said housing, a spring support adapted to be selectively mounted within said housing at either side of the bolt pivot, the swinging end of said support being slidably engaged with said bolt, a spring mounted on said bolt to engage the swinging end of said support, coacting detents and keepers on said housing and bolt adapted to support the bolt in retracted position when

swung in either direction from a central position, and spaced stops on said housing co-acting with the swinging end of said support.

13. In a latch, the combination with a housing, of a bolt pivotally mounted in said housing, a spring support adapted to be selectively mounted within said housing at either side of the bolt pivot, the swinging end of said support being slidably engaged with said bolt, a spring mounted on said bolt to engage the swinging end of said support, and coacting detents and keepers on said housing and bolt adapted to support the bolt in retracted position when swung in either direction from a central position.

14. In a latch, the combination with a housing of a bolt pivotally mounted in said housing, a spring support adapted to be selectively mounted within said housing at either side of the bolt pivot, the swinging end of said support being slidably engaged with said bolt, a spring mounted on said bolt to engage the swinging end of said support, and spaced stops on said housing co-acting with the swinging end of said support.

15. In a latch, the combination with a housing, of a chambered bolt pivotally mounted in said housing, a spring support pivotally mounted within said housing at one side of the bolt pivot, the swinging end of said support being slidably engaged with said bolt, a spring supported within said bolt to engage the swinging end of said support, co-acting detents and keepers on said housing and bolt adapted to support the bolt in retracted position, and a stop on said housing coacting with the swinging end of said support.

16. In a latch, the combination with a housing, of a bolt pivotally mounted in said housing, a spring supporting link slidably engaged at one end with the bolt and adapted to be selectively pivoted at either side of the bolt pivot, and a spring mounted on the bolt to act on the swinging end of said link.

17. In a latch, the combination with a housing, of a bolt pivotally mounted in said housing, a spring supporting link slidably engaged at one end with the bolt and adapted to be selectively pivoted at either side of the bolt pivot, and a spring acting on the swinging end of said link.

18. In a latch, the combination of a housing, a bolt pivotally mounted in said housing, said housing having an opening in its front wall permitting a free swinging of the bolt in either direction from a central position, a spring support having sliding engagement with the bolt and adapted to be selectively pivoted at either side of the bolt pivot, and a spring acting on the swinging end of the support.

19. In a latch, the combination with a housing, of a bolt pivotally mounted in said hous-

ing, a link pivotally mounted in said housing in spaced relation to the bolt pivot, the swinging end of said link being slidably engaged with the bolt, and a spring arranged within said bolt to engage the swinging end of said link.

20. In a latch, the combination with a housing, of a bolt pivotally mounted in said housing, a link pivotally mounted in said housing in spaced relation to the bolt pivot, the swinging end of said link being slidably engaged with the bolt, and a spring acting on the swinging end of said link.

In witness whereof I have hereunto set my hand.

GORDON E. ROEDDING.
